UNITED STATES PATENT OFFICE.

GEORGE M. SPENCER, OF ST. LOUIS, MISSOURI, ASSIGNOR, BY MESNE ASSIGNMENTS, TO
NATIONAL PNEUMATIC COMPANY, A CORPORATION OF WEST VIRGINIA.

PNEUMATIC OPERATING MECHANISM FOR DOORS, STEPS, OR THE LIKE.

1,134,648.

Specification of Letters Patent.

Patented Apr. 6, 1915.

Application filed June 2, 1909. Serial No. 500,917.

To all whom it may concern:

Be it known that I, GEORGE M. SPENCER, a citizen of the United States, residing at St. Louis, in the State of Missouri, have made a certain new and useful Invention in Pneumatic Operating Mechanism for Doors, Steps, or the like, of which the following is a specification.

This invention relates to pneumatic operating mechanism for doors, steps or similar devices.

The object of the invention is to provide means whereby when the door or other device to be operated, is at rest the pressure medium is exhausted from both ends of the operating cylinder, or from both sides of the operating piston.

A further object is to provide means whereby the operating pressure is cut off before the end of the stroke of the operating piston whereby the completion of the operation of the door or other device to be moved, is effected by the expansion of the pressure medium already supplied to the cylinder.

Other objects of the invention will appear more fully hereinafter.

The invention consists substantially in the construction, combination, location and relative arrangement of parts, all as will be more fully hereinafter set forth, as shown in the accompanying drawing and finally pointed out in the appended claims.

Referring to the accompanying drawing, and to the various views and reference signs appearing thereon, Figure 1 is a view in elevation showing a pneumatic door operating mechanism embodying the principles of my invention. Figs. 2, 3 and 4 are diagrammatic views illustrating the valve action. Fig. 5 is a diagrammatic view illustrating the connections from the valve to the cylinder. Fig. 6 is a view in side elevation of the valve.

45 The same part is designated by the same reference sign wherever it occurs throughout the several views.

In the practical operation of pneumatic mechanism for opening and closing doors, moving steps, or other devices, where a pressure medium, such as compressed air, is admitted to a cylinder to operate a piston, it is a common practice to open one end of the cylinder to exhaust at the same time 55 the other end is opened to admit the pres-

sure medium. Thereupon the door or other device to be operated is started on its movement as soon as the operating pressure admitted to the cylinder, or to one side of the operating piston is sufficiently in excess 60 of the retarding pressure offered by the escaping exhaust at the other end of the cylinder, or on the other side of the piston, to develop the required power to overcome friction and the inertia of the door or other 65 device to be operated. The door or other device then continues to move, provided it encounters no obstruction, at a speed dependent upon the rate of exhaust, or the difference between the operating and exhausting 70 pressures, until it reaches its final limit of movement. When this final limit is attained, the operating pressure remains applied to one end of the cylinder or to one 75 side of the operating piston, and the other end of the cylinder or the other side of the piston remains open to the exhaust, until it is desired to operate the door or device in the other direction when, through a valve or other form of controller the above operation 80 is reversed. It has been found by practical experience that in the operation of pneumatic mechanism of the character referred to, and especially in the operation of doors and steps or like devices, leakage of the 85 pressure medium occurs through the piston packing and other joints which develops decided objections. This is especially true of the operation of doors and steps on cars, for instance, since by far the greater portion 90 of the time the doors remain closed, and the constant application of the pressure medium to the operating piston while the door remains closed affords an opportunity for leakage of the pressure medium, and while such leakage may be small, in the aggregate of a day's operation, for instance, it becomes a material factor in the operation 95 of the system. Again, where pressure in one end of the operating cylinder while the 100 door or other device remains in the limit of its movement, as, for instance, in its closed position, if a door, and it is desired to open the door, an appreciable interval of time must elapse before the door commences its 105 opening movement to enable the pressure in the previously open end of the cylinder to overcome the exhausting pressure in the previously closed end of the cylinder. Again, in case the door or other device to 110

be operated is forcibly detained or held before its limit of movement is reached, the exhaust continues on one side of the operating piston while the pressure on the other side continues to build up till it reaches the full tank or reservoir pressure with the result that when the detaining obstruction is removed the door will move to its limit of movement with an objectionable

10 slam.

It is among the special objects and purposes of my present invention to overcome these and other difficulties encountered in the operation of apparatus of this nature, 15 and in carrying out my invention I propose to provide means whereby when the door or other device to be operated is at rest the pressure medium is equalized on, or exhausted from, both ends of the cylinder, or 20 from both sides of the operating piston. I also propose to provide means whereby the operating medium is cut-off before the door or other device to be operated reaches the limit of its movement, whereby the expansion 25 of the supplied pressure medium is utilized in completing the movement of the door. And in accordance with my invention I propose to employ automatic means for accomplishing these results.

30 Many specifically different constructions and arrangements may be provided for carrying the objects and purposes of my invention into practical operation. While, therefore, I have shown, and will now describe, one construction and arrangement, I desire it to be understood that my invention in its broadest scope, and as defined in the claims, is not to be limited or restricted to the exact construction and arrangement 35 shown.

In the drawing reference sign A designates the device to be operated, in this case a door; B, the arm connected thereto to operate the same; C, the power cylinder; 45 D, the valve casing in which operates the valve for controlling the supply and exhaust of operating medium to and from the cylinder. In the form shown the cylinder is a double cylinder, or two cylinders arranged 50 in alignment with each other, with the pistons E, F, respectively operating in said cylinders, and connected together by a rack G; the remote ends of the double cylinder being closed and the proximate ends there- 55 of being open to the atmosphere. The operating arm B, is formed on or connected to a segment gear 8, which meshes with and is actuated by the rack G. This gear is pivoted as at 30 upon the standard H, formed on the 60 cylinder casting or frame, and the pivot stud thereof is provided with a crank arm 9.

Pivotedly mounted as at 2, on the upper end of standard H, is a curved piece 1, having its curved ends extending on opposite

sides of the pivot point 2. Adjustably 65 mounted on these ends, respectively, are the lugs or blocks 3, 4. Connected to the pivot pin of curved member 1, is a crank arm 5, having connection through rod 6, with a trip arm 7, which is connected to the valve in 70 casing D. The relation of the stop blocks or lugs 3, 4, with reference to the crank arm 9, is such that when the operating arm B, is rocked sufficiently far in one direction or the other, the end of crank arm 9 75 engages the one or the other of the stop blocks 3, 4, as the case may be, thereby rocking the member 1, and, through the rocking movement thereof, operating the valve. The engaging ends of the crank arm 9, and 80 the stop blocks 3, 4, are so shaped that after the crank arm has engaged a stop block and operated the member 1, the crank arm may continue its movement by wiping past the stop block. The stop lugs 3, 4, being 85 adjustably mounted on the rocking member 1, they can be so set, or the position thereof so adjusted that the arm 9, will engage and move the same; and hence actuate the valve, at any desired point in the stroke of the 90 piston, and can then continue its movement without affecting any further valve movement.

In Figs. 2, 3, and 4, I have shown diagrammatically the under side or working 95 face of the valve 31, the ports in the valve seat 32, see Fig. 6, being indicated in dotted lines. The valve seat is provided with four ports 10, 11, 12 and 13. The ports 10 and 11, respectively communicate with the 100 remote ends of the cylinder, through pipes 33 and 34. The port 12, communicates with a source of pressure supply, and the port 13, with the exhaust. The double cylinder is provided with the port openings 14, 15, 105 to the atmosphere which openings are controlled by the pistons E, F. These openings 14, 15 are arranged so as to be uncovered by the pistons when they approach the respective limits of their stroke in operating direction, thereby opening the respective cylinders to atmosphere. When the valve 31, occupies the position shown in Fig. 2, the pressure supply port 12, is opened to the port 10, and thence, through 110 pipe 33, to the left hand end of the cylinder. At the same time the port 11, which communicates with the right hand end of the cylinder, is opened to exhaust port 13. But since the piston F, at this time has uncovered port 15 there is no pressure in the 115 right hand end of the cylinder, and therefore at the beginning of the movement of the connected pistons toward the right there is no pressure in the right hand end of the 120 cylinder to oppose the operating medium supplied through the ports 12, and 10, to the left hand end of the cylinder, and con-

sequently the door begins to move instantly the valve is operated to the position shown in Fig. 2, and with a less degree of operating pressure than would be required if there was an opposing pressure in the right hand of the cylinder. It is desirable, however, as the door continues its movement, to build up an opposing pressure, or a resistance in the right hand end of the cylinder so as to prevent the door from slaming, as well as to prevent accident or injury in case a person or other obstruction should impede the movement of, or be encountered by the door. This is accomplished in the following manner: It will be observed that the valve 31, is provided with an extension 35, of the recess 36, therein, a lip or flange 37, of the valve intervening between such extension and the valve seat. Through this lip or flange are formed a series of small holes 16, 17, 18. It will also be observed, that shortly after the piston F, starts to move toward the right, under the conditions mentioned, it will close port 14, thereby confining whatever atmospheric air the right hand end of the cylinder may contain from the previously opened port 14. This air can escape, only through one of the restricted openings 16, 17, 18, according to the position of the valve, and thence through the exhaust port 13. The amount of this exhaust will, of course, be dependent upon the area of the small opening 16, 17 or 18, through which the exhaust is effected. The areas of these openings are calculated according to and depend largely upon the amount of pressure that is being used, and upon the point at which it is desired the cushioning should commence, the weight and friction of the door or other part to be moved, and other like conditions. In actual practice, using the ordinary pressure of 60 to 100 pounds commonly employed in street car work it has been found that the opening 16, may be entirely dispensed with, as all the atmospheric air in the cylinder should be retained during the first part of the stroke of the piston in order that sufficient back pressure may be built up to properly cushion the operating pressure during the latter part of the stroke. Toward the end of the stroke, however, the momentum of the door having been partially restrained by the building up cushion, and the operating pressure being reduced by expansion, it is desirable that the back pressure or cushion pressure be also reduced, and this is accomplished by causing one or the other of the larger openings 17 or 18, to be brought into register with the exhaust port 13. In case the operating or tank pressure is quite low, say 30 pounds, a small opening 16 is desirable, as otherwise the back pressure or cushion might build up sufficiently to equal or exceed the operating pressure at a point too early in the operation of the door. After the valve has been operated to the position shown in Fig. 2, the operation above described is inaugurated and at a certain point in the operation thus initiated, the position of the valve is shifted automatically through the connections above described, into the position shown in Fig. 4, thereby cutting off entirely the further supply of pressure to the left hand end of the cylinder through port 10. Thereafter the expansion of the operating pressure previously supplied to the left hand end of the cylinder is utilized to complete the movement of the door. The amount of operating pressure in the cylinder at the moment this cut-off takes place has no direct relation to the tank or reservoir pressure, as it is dependent solely on the power required to move the door, the ports 10, 11 and 12, being made, in practice, sufficiently small to prevent the operating pressure to enter the cylinder too rapidly, and since there is no exhaust pressure in the opposite end of the cylinder to expel, the door will start to move the instant the operating pressure is sufficient to overcome the inertia, friction, &c. The operating pressure in the cylinder, therefore is governed solely by the pressure required to move the door and is not complicated by the length of time the door might linger before starting to move. This is a most desirable feature of my invention since in devices of this nature as heretofore employed where there is exhaust pressure to be taken into consideration, the length of time the door lingered before starting very greatly affects the operating pressure. Referring again to Fig. 3 it will be seen that not only is port 10 cut off from the pressure supply but the exhaust port 13, communicates with the cylindrical port 11, through the small hole 17, instead of hole 16, and hence through a hole of somewhat larger area to compensate for the reduced expansion pressure in the operating end of the cylinder. When the operating piston reaches the limit of its movement toward the right, the piston E uncovers the port 14, thereby opening the left hand end of the cylinder to exhaust, and hence not only equalizing the pressure at both ends of the cylinder, or on both sides of the piston, but also avoiding the opportunity of leakage of pressure in the operating cylinder or past the piston packings, or other joints thereof. When it is desired to actuate the operating piston toward the left the valve is shifted into the position indicated in Fig. 3, thereby repeating, in the apparatus the operation above described except that now the operating or tank pressure is supplied to the right hand end of the cylinder, while the

compression or cushioning effect is secured in the left hand end.

The valve may be initially operated in any suitable manner and by any suitable arrangement of connections, and from any convenient point. I have shown a control handle *J*, connected through intermediate devices *K*, for this purpose.

From the foregoing description it will be seen that I avoid leakage of the pressure medium. It will also be seen that the cylinder is exhausted of operating medium at both ends when the door is at rest. By reason of this feature it follows that by operating the control handle to its extreme position in either direction the door is moved by power mechanism, in the one direction to be opened and in the other direction to be closed, and when such control handle is moved to centered or half way position the power medium is shut off, both ends of the cylinder is opened to exhaust, and thereafter the door may be moved by hand to any position. This is a desirable feature especially in the case of the use of my invention in connection with the doors of elevated, surface, subway or street or other cars, where large crowds are handled as thereby I avoid the necessity of forcing, by power mechanism, the doors shut through a crowd of passengers who are only partially inside the door. In this case the control handle is placed in central position and the door may then be closed by hand. It will also be seen that the door begins to move instantly upon applying the operating pressure, and that I utilize the expansion of the operating medium, after the supply thereof is cut off, to complete the operation of the door or other device to be operated.

Having now set forth the object and nature of my invention and a construction embodying the principles thereof, what I claim as new and useful and of my own invention and desire to secure by Letters Patent is:

1. The combination with a device to be moved, of pressure actuated operating means therefor, including a cylinder and piston, a valve for controlling the supply and exhaust of pressure medium to both ends of the cylinder, and operating when in centered position to open both ends of the cylinder to exhaust, and means for centering the valve as the device to be moved attains the limit of its movement.

2. The combination with a device to be moved, of pressure actuated operating means therefor, including a cylinder and piston, a valve to control the supply and exhaust of operating medium to and from the cylinder, and operating, when in centered position, to open both ends of the cylinder to exhaust, and automatically operated

means for centering the valve as the device to be moved attains the limit of its movement.

3. The combination with a device to be moved, of a cylinder and piston for operating the same, and automatic means for simultaneously exhausting the pressure on opposite sides of the piston as the device to be moved attains the limit of its movement.

4. The combination with a device to be moved, of an operating cylinder and piston, the pressure on both sides of the piston being equalized when said device attains the limit of its movement, manually operated means for admitting the pressure to one side of the piston and means for restricting the exhaust from the opposite side of the piston, means for cutting off the supply on the pressure side of the piston automatically before the device to be moved attains the limit of its movement and means for coincidentally enlarging the area of the exhaust on the other side of the piston.

5. The combination with a device to be moved, of a double cylinder, connecting pistons operating therein, connections operated by the pistons for moving said device, and automatically operated means for simultaneously exhausting the pressures on opposite faces of the piston at the limit of their stroke.

6. The combination with a device to be moved, of cylinders arranged in alignment with each other, connected pistons respectively operating in said cylinders, means operated by said pistons for moving said device, manually operated devices for controlling the supply and exhaust of pressure medium to and from the remote ends of said cylinders and atmospheric exhaust openings at the proximate ends of said cylinders, said exhaust openings being uncovered by said pistons respectively as they reach the limits of their out stroke.

7. The combination with a device to be moved of cylinders arranged in alignment with each other, connected pistons respectively operating in said cylinders, means operated by said pistons for moving said device, said cylinders being opened to the atmosphere at their proximate end and closed at their remote end, means manually operated for controlling the supply and exhaust of operating medium to and from the remote ends of said cylinders, and exhaust port formed in said cylinders adjacent their proximate ends, said exhaust ports being controlled by the pistons.

8. The combination with a device to be moved, of a cylinder and piston, a rack operated thereby, a pivoted segment gear operated by the piston and connected to said device for operating the same, a stand-

ard on which said gear is pivotally supported, a rocking member carried by said standard and having adjustable stops, a valve mechanism, connections between said rocking member and valve mechanism, and means operated by the gear to engage said stops.

In testimony whereof I have hereunto set

my hand in the presence of the subscribing witnesses, on this first day of June, A. D., 1909.
